UNITED STATES PATENT OFFICE.

PATRICK HENRY BARKER, OF CHICAGO, ILLINOIS, ASSIGNOR OF ONE-HALF
TO ALBERT HEINE, OF SAME PLACE.

DESIGN FOR A BICYCLE-HUB:

SPECIFICATION forming part of Design No. 30,116, dated January 31, 1899.

Application filed October 17, 1898. Serial No. 693,832. Term of patent 7 years.

To all whom it may concern:

Be it known that I, PATRICK HENRY BARKER, a citizen of the United States, residing at Chicago, in the county of Cook and State 5 of Illinois, have invented and produced a new and original Design for a Bicycle-Hub, of which the following is a specification, reference being had to the accompanying drawings, in which—

10 Figure 1 is an end elevation of a bicycle-hub showing my new design, Fig. 2 a front elevation of such hub, and Fig. 3 a perspective view thereof, all such figures being necessary to exhibit the same.

15 A reference-letter applied to designate a given part is used to indicate such part throughout the several figures.

As shown in the drawings, the leading or material feature of my design consists of the

spoke-flanges $a a'$ on and concentric with the 20 barrel A, apertures B B' giving a light and graceful appearance to the flanges, such apertures disposed or arranged as shown in Figs. 1 and 3, and the beads D D' extending circumferentially around the spoke-flanges on the 25 side faces thereof adjacent to the peripheral edges of such spoke-flanges, such beads not being pronounced in character. The spoke-flanges $a a'$ are provided with the ordinary holes for attaching wire spokes thereto, such 30 holes being lettered C C'.

What I claim is—

The design for a bicycle-hub herein shown and described.

PATRICK HENRY BARKER.

In presence of—

ALBERT HEINE,
F. L. BROWN.
